US00D976951S

(12) **United States Design Patent** (10) Patent No.: **US D976,951 S**
(45) Date of Patent: **** Jan. 31, 2023**

(54) **PACKAGE WITH SURFACE
ORNAMENTATION OR DISPLAY SCREEN
WITH ICON**

(71) Applicant: **Kimberly-Clark Worldwide, Inc.**,
Neenah, WI (US)

(72) Inventors: **Samantha R. Goss**, Greenville, WI
(US); **Valerie Michelle Aurillo**,
Naperville, IL (US); **Hannah Elizabeth
Motz**, Evergreen Park, IL (US);
Benjamin Arthur Warner, Trenton,
OH (US)

(73) Assignee: **Kimberly-Clark Worldwide, Inc.**,
Neenah, WI (US)

(**) Term: **15 Years**

(21) Appl. No.: **29/770,718**

(22) Filed: **Feb. 16, 2021**

(51) LOC (14) Cl. **14-04**

(52) U.S. Cl.

USPC **D14/489**

(57) **CLAIM**

The ornamental design for a package with surface ornamentation or display screen with icon, as shown and described.

DESCRIPTION

The FIGURE is a front view of the claimed design for a package with surface ornamentation or display screen with icon.

The uneven-length broken lines immediately adjacent to the claimed area depict boundaries of the claimed design and form no part thereof.

The even-length broken lines showing the package or display screen form no part of the claimed design.

1 Claim, 1 Drawing Sheet
